UNITED STATES PATENT OFFICE.

ANDREW J. MORTON, OF LOS ANGELES, CALIFORNIA.

TWIN OIL-BURNER.

1,159,249.

Specification of Letters Patent.

Patented Nov. 2, 1915.

Application filed May 22, 1915. Serial No. 29,904.

To all whom it may concern:

Be it known that I, ANDREW J. MORTON, a citizen of the United States, residing at Los Angeles, in the county of Los Angeles and 5 State of California, have invented a new and useful Twin Oil-Burner, of which the following is a specification.

This invention relates to that class of hydrocarbon burners in which steam or other 10 elastic fluid is used to spray oil into the fire-box or furnace, and to cause the same to break up and to become atomized and mixed with air for perfect combustion.

Objects of the invention are to provide an 15 oil burner of this description which is cheap and simple to manufacture; which will atomize the oil and distribute it in the furnace in such a way as not to be destructive to the side walls of the fire-box; also to provide 20 for ready and convenient cleaning of the burner if it becomes clogged with accumulations of asphaltum, hardened carbon or foreign matter.

The accompanying drawings illustrate the 25 invention.

Figure 1 is a perspective view of a burner constructed in accordance with this invention. Fig. 2 is a perspective view of the burner elements dismantled, omitting the 30 screws and pipes shown in Fig. 1, the upper plate being turned upside down to expose the inside construction. Fig. 3 is a plan of the body of the burner from which the detachable plates have been removed. Fig. 4 35 is a plan of the separating plate detached. Fig. 5 is a view of the bottom of the burner detached. Fig. 6 is a front view of the burner detached. Fig. 7 is a longitudinal section of the burner on irregular line x^7-x^7 , 40 Figs. 3 to 6. Fig. 8 is a fragmental vertical section on line indicated at x^8-x^8 , Fig. 5.

The body of the burner comprises a stock 1, and a lip 2 projecting forwardly from the lower part of the stock, which is thus practically recessed to receive detachable superposed elements to form mixing and discharge passages. Said stock is provided with two superposed longitudinal bores 3, 4, opening into the recess 5. The upper face 45 of lip 2 is channeled at 6, 7, 8 to form in conjunction with a superposed element an expansion chamber at 6 and two outlets at 7, 50 8 opening forwardly therefrom, there being at the sides of the lip, two side walls 9, and

there also being at the front a rib 10 separating the two outlet channels 7, 8. The tops of said side walls and rib are in a common horizontal plane toward which the floors of the channels 7, 8 slope upwardly. The wall 11 of the stock at the rear of the 60 lip is inclined rearwardly and superposed plates 12 and 13 rest against said wall.

The separating plate 12 may be a piece of sheet metal of any appropriate thickness, say for instance, about $\frac{3}{16}$ of an inch thick, 65 the same being fitted upon the tops of the side walls and the rib.

The upper plate or cap 13 is channeled like the lip so as to form, in conjunction with the separating or intermediate plate, 70 the distributing chamber 14, and the outlets 15, 16 therefrom; there being at the sides of said upper plate two side walls 17, 18 and there also being a rib 10' lying between and separating the outlet channels. The lateral 75 extension of the issuing jets of expansive fluid will be effected mainly by the expansion of the fluid after leaving the channels. In practice said jets strike upon each other at some distance from the burner, the result 80 being that the edges of the two flat jets will impinge upon the air close to the burner in the space between said jets, and will entrain the air into the middle of the final wide flat jet resulting from the union of the two issuing 85 flat jets of steam.

The burner may be installed by screwing the steam and oil pipes 19, 20 into the bores 3, 4 in the stock of the burner; said pipes then being connected in any usual way with 90 the sources of steam and oil supplies. The plates 12, 13 are fastened in superposed position on the lip 2 by means of machine screws 21, 22; said screws being provided with cylindrical bodies b to pass through 95 the holes 23, 24 prepared in the plates to receive said bodies. The lip is provided with threaded holes 25, ready to receive the threaded ends c of the machine screws.

There are preferably three machine screws 100 used at the tip of the burner, and two other screws of like character near the stock 1; the smooth holes 23 therefor being bored through the central rib 10 and the side walls 17 of the top plate, and there being threaded 105 holes 25 for the threaded tips of said screws in the lip. The ends of the plates that are to abut against the wall are beveled to fit

tightly against the wall, and when the five screws are screwed home firmly, they close the joint between the plates, the stock, and the lip, so that no steam or oil will escape from the burner except through the channels provided therefor.

The tip of the burner is provided with two forward extensions 27, 28 each of which is outwardly curved thus leaving a central recess 29, adjacent the front ends of the ribs 10, so as to give free access of air to the space between the jets issuing from the channels. The bottom of the lip 2 and the top of the top plate, are also recessed as indicated at 30 and 31, to allow a freer passage of air to the recess between the jets.

In practical operation the steam expands in the expansion chamber therefor and flows through the outlet ports under a regulated pressure determined by the steam pressure supplied through the steam pipes, thin flat twin steam jets being thus discharged edge to edge in a common plane. The oil will also be supplied under an appropriate pressure and will fill the feed chamber and the outlet ports leading therefrom so that the liquid hydrocarbon will be delivered in a predetermined stream to the space above the steam outlets and will fall onto the flat issuing jets of steam. By preference the steam outlets are slightly wider than the oil outlets, so that the oil streams will not escape downward past the steam jets that are designed to receive them. The action of the steam or other expansible fluid used, will be to tear up the oil and to thoroughly mix the same with entrained air, at the middle as well as at the edges of the final united jet, and when ignition occurs, the fuel is vaporized and burnt in a highly economical and efficient manner, expansion of the gases practically filling the fire-box, not shown.

The outlets for the oil are directly above the outlets for steam and are narrower than and spaced farther apart than the steam outlets, so that air is entrained to the steam between the oil jets or streams, thus increasing the effectiveness of the mixture of air and oil during the operation of the burner.

The body of the burner, including the stock and lip; and the upper plate of burner also, may be made of cast brass or other suitable material, and the separating plate may be made of sheet brass or other suitable material stamped or otherwise cut into the desired form. The screws may be steel or other suitable metal.

By changing the angle of the inner face of the side walls, the jets are made to flow in any desired direction so as to avoid destructive action on the side walls of the furnace or fire box. Such change may be made by filing or otherwise cutting said walls as required.

In case of clogging or stopping of the

channels, the screws may be removed and the plates taken off and the channels cleaned out. Thereupon the plates may be restored and the burner will again be ready for operation.

70

It is thus seen that I have provided superposed chambers and pairs of outlets therefrom, the pairs of outlets being spaced apart to admit air to be entrained between them, thus producing twin jets that become united 75 after entraining air between them.

I claim:

1. An oil burner provided in a common plane with two outlets for elastic fluid, and in a higher plane with two outlets for oil; 80 the outlets for oil being narrower and spaced apart farther than those for the elastic fluid.

2. An oil burner comprising a body having a stock and a lip, said lip being provided with a chamber and channels leading 85 therefrom, there being on the upper face of said lip side walls for said chamber and channels and a rib between said channels; an intermediate plate to rest on the tops of said rib and side walls; a top plate provided 90 with side walls and a rib and with a chamber and two outlets between said side walls, said rib separating said outlets, and means to fasten said intermediate plate on the lip and said top plate on the intermediate plate; 95 the ribs and side walls of the lip and top plate forming tight joints with the intermediate plate; there being a steam inlet to the chamber below the intermediate plate and an oil inlet to the chamber above the intermediate plate. 100

3. An oil burner comprising a body having a stock and a lip, a top plate and an intermediate plate on said lip; there being a chamber and channels leading therefrom below the intermediate plate; there also being a chamber and outlet therefrom above the intermediate plate; said plates being superposed and there being inlets through the stock to said chambers; and means to fasten said 110 superposed plates on the lip and against the stock. 105

4. A burner comprising a body, a lip, and plates arranged to form two superposed chambers and pairs of outlets therefrom, the 115 pairs being spaced apart from each other to admit air to jets issuing from the outlets, and means to fasten the parts together.

5. An oil burner comprising a body having a stock and a lip, said lip being provided with side walls for a chamber, and channels forming a pair of outlets leading from said chamber, and also provided with a rib between said side walls to separate the channels; an intermediate plate to rest on 120 the tops of said rib and side walls, and a top plate provided with a chamber and a pair of outlets leading from the chamber, and means to fasten said plates and the lip together; the ribs and side walls of the lip 130

and top plate forming tight joints with the intermediate plate, the top and bottom of said burner being recessed to give free access of air to the space between said pairs of outlets.

6. A burner provided with two pairs of outlets, said pairs being spaced apart to admit air between said outlets, the tip of the burner being recessed at top and bottom

and extended in an arched form on opposite sides of the recess.

In testimony whereof, I have hereunto set my hand at Los Angeles, California this 15th day of May, 1915.

ANDREW J. MORTON.

In presence of—
JAMES R. TOWNSEND.
